(57) **CLAIM**

The ornamental design for a clip for a headset, as shown and described.

DESCRIPTION

FIG. 1 is a front perspective view of a clip for a headset showing my new design;

FIG. 2 is a top view thereof;

FIG. 3 is a bottom view thereof;

FIG. 4 is a rear perspective view thereof; and,

FIG. 5 is a left side view thereof.

The broken line showing environmental structure is for illustrative purposes only and forms no part of the claimed design.

1 Claim, 5 Drawing Sheets**FIG. 1**

FIG. 2

FIG. 3

FIG. 4

FIG. 5
